MICROPHONE

Charles E. Fraser, Rockville Centre, N. Y.

Application January 23, 1945, Serial No. 574,181

6 Claims. (Cl. 179—1)

(Granted under the act of March 3, 1883, as amended April 30, 1928; 370 O. G. 757)

This invention relates to an apparatus for converting sound vibrations into electrical variations, and more particularly to a microphone adapted to minimize the disturbing effects of undesired sound waves and audioregeneration, or feed-back.

Most particularly, it is an object of my present invention to provide an improved microphone which will respond more readily to desired than undesired sound vibrations.

A further object of my present invention is to provide an improved microphone of the electro-acoustic transducer type selective with respect to sound waves originating at different positions and distances relatively to the microphone.

Still another object of my present invention is to provide an improved microphone which will substantially convert into electrical impulses, only sound vibrations originating in a predetermined localized region with respect to the microphone.

It is also an object of my present invention to provide a microphone employing a pair of concentrically positioned diaphragms in which stray noises affect both of the diaphragms while desired sounds are focused upon only one of them.

In certain types of announcing or public address systems, particularly aboard ship, and in industrial plants, permanent electrical amplifiers and loud-speaker systems are installed and provided with a multiple of input jacks, or terminals, into which the announcer may plug-in or connect a portable microphone at any of the various stations distributed about the ship, or throughout the industrial plant. Under such conditions there are usually stray noises due to the operation of machinery and from other sources, so that when microphones of the conventional type are used the announcement may be rendered unintelligible due to the stray noises or from regenerative audio feed-back.

In underwater detection, particularly where conventional microphones are utilized aboard moving vessels, local sound vibrations generated by the machinery and propellers aboard the vessel on which such microphones are located are detrimental with respect to the distance and identities of sound vibrations emanated by remote targets.

It is among the more particular objects of this invention to provide a microphone and system which will substantially overcome these disadvantages and reproduce to greater extent the desired sounds.

These objects, and such objects as will herein-

after appear or be pointed out, will best be understood from the following description of several embodiments thereof, when read in connection with the accompanying drawing, in which

5 Figure 1 is a schematic diagram indicating an electrical system which may be employed.

Figure 2 is a sectional view of two electrodynamic microphones and associated electrical connections.

10 Figure 3 is a schematic diagram indicating the electrical connections of the moving coil elements.

Figure 4 is a sectional view of one form of my improved microphone with the cover partially shown.

Figure 5 is a face view of the plate diaphragm in reduced scale.

Figure 6 is a face view of the ring diaphragm in reduced scale.

20 Figure 4 shows one form of microphone embodying my invention wherein circular permanent magnet 1 is housed in casing 3 and provided with circular slots 2 and 2a. Plate diaphragm 4 (as shown in Figure 5) and ring diaphragm 5, (shown in Figure 6) are concentrically positioned in spaced relation with magnet 1 and support magnetic windings or coils 6 and 7 respectively, which operate within the magnetic field of slots 2 and 2a respectively, and thereby generate an electromotive force whenever diaphragms 4 and 5 are set into vibration. Cover cap 8 is provided with a threaded extension 9 to which a sound directing extension 10, provided with a series of holes 11, may be attached and

25 adapted to direct desired and undesired sound waves onto diaphragm 4. Cap 8 is also provided with a series of apertures 12 whereby undesired sound waves may be impressed on ring diaphragm 5. Extension 9 is extended toward diaphragm 4 and serves to prevent the desired vibrations from reaching ring diaphragm 5. It will be readily understood that undesired sound vibrations will be impressed upon diaphragms 4 and 5 as indicated by arrows 13 and 13a.

30 45 In Figure 2 the action of the two diaphragms, previously referred to in Figure 4, and the electrical circuit connections of the coils in opposed polarity are shown. In this figure apertures 12 of Figure 4 are indicated as sound director 12a.

50 In Figure 2 the operation of this microphone is more clearly indicated by showing the permanent magnets 1 and 1a, diaphragms 4 and 5a, and coils 6 and 7a with associated sound directing devices 10 and 12a. In this figure the circuit 55 connections in reversed polarity to the serially

connected coils 6 and 7a clearly indicate that when sound vibrations of equal magnitude and phase relationship are impressed simultaneously on diaphragms 4 and 5a the current generated in coils 6 and 7a will balance in opposed polarity and substantially no current will therefore flow to the loud-speaker.

Figure 3 indicates the wiring diaphragm of serially connected coils 6 and 7 (Figure 4) in opposed polarity relationship and their resulting cancellation action when set into vibration by sound waves of equal magnitude and phase as indicated by arrows 13 and 13a.

Figure 1 indicates one form of schematic wiring diagram embodying an amplifier 14, a loud-speaker 15, and a series of jacks 16 into which microphone 17, connected by means of flexible conductor 18 to plug member 19, may be connected. This indicates the system usually used aboard ship and in industrial plants where announcements are made from various stations by means of a portable microphone carried by the announcer.

It will be readily understood that all parts of my invention may be made of suitable materials well known in the art to which it pertains and that the various parts may be dimensioned and designed to render them suitable for operation under whatever condition and purpose my invention is to be utilized.

From the foregoing description it will be apparent to those skilled in the art that I have provided an improved microphone which is more sensitive to desired than undesired sound waves than are conventional microphones. Although, I have shown and described several embodiments of my present invention, it will be apparent to those skilled in the art that many other modifications thereof are also possible. For example, I may use microphone elements of the crystal, condenser, thermal, ribbon, or other suitable type with their required associated circuits. I therefore do not wish to be limited except insofar as is made necessary by the prior art and by the spirit of the appended claims.

The invention described herein may be manufactured and used by or for the Government of the United States of America for governmental purposes without the payment of any royalties thereon or therefor.

I claim as my invention:

1. In combination, a magnetic microphone having two concentric diaphragms each provided with a coil, means for directing desired and undesired sound waves upon said diaphragms, and means whereby the currents generated in said coils by the action of said diaphragms due to the undesired sound waves are substantially annulled.
2. In combination, a magnetic microphone having two concentric diaphragms each provided with a coil, a circular magnet provided with concentric slots in which said coils operate, means for directing desired and undesired sound waves upon said diaphragms, and an electrical system whereby the currents generated in said coils by the action of said diaphragms due to undesired sound waves are substantially annulled.
3. In combination, a magnetic microphone having two concentric diaphragms each supporting a coil, a magnet provided with concentric slots in which said coils operate, means for directing desired and undesired sound waves upon said diaphragms, said coils being serially connected in opposed polarity whereby the currents generated by the action of said diaphragms due to undesired sound waves are substantially annulled.
4. In a microphone, a pair of electroacoustic elements concentrically located, means for impressing desired sound waves on one of said elements, means for impressing undesired sound waves on both of said elements, and means for permitting the effects of the desired sound waves to predominate.
5. In a microphone, a pair of concentric diaphragms, means for impressing desired sound waves on one of said diaphragms, means for impressing undesired sound waves on both of said diaphragms, and means for permitting the effects of the desired sound waves to predominate.
6. In a microphone, a pair of concentric diaphragms, means for impressing desired sound waves on one of said diaphragms, means for impressing undesired sound waves on both of said diaphragms, and means for substantially neutralizing the effects of the undesired sound waves whereby the effects of the desired sound waves predominate.
